INVENTOR.

JAMES J. SUNDAY

BY Whittmore & Hubert

Whittmore & Belknap

ATTORNEY.

UNITED STATES PATENT OFFICE.

JAMES J. SUNDAY, OF DETROIT, MICHIGAN, ASSIGNOR, BY MESNE ASSIGNMENTS, TO KELCH VENTILATING HEATER COMPANY, A CORPORATION OF MICHIGAN.

REGISTER.

Application filed August 11, 1925. Serial No. 49,538.

This invention relates generally to heating apparatus and refers more particularly to hot air registers designed for use within vehicle bodies and the like.

- One of the essential objects of the invention is to provide a neat and compact register that may be manufactured for a comparatively low cost and can be easily and quickly installed within a vehicle body and the like. Another object is to provide a register of this type that preferably consists of relatively few parts which may be readily cleaned, repaired or replaced when desired.
- A further object is to provide a strong and durable register having an air supply passage and a dirt outlet which are controlled by a single valve that may be easily and conveniently actuated by simple and reliable operating means.

With the above and other objects in view, the invention consists of certain novel features of construction, combinations and arrangements of parts as will be more fully described and particularly pointed out in the appended claims.

In the accompanying drawings:

Figure 1 is a fragmentary side elevation of a vehicle body with a register embodying my invention mounted thereon.

Figure 2 is a top plan view of the register.

Figure 3 is a vertical sectional view through the register.

Figure 4 is a horizontal section through the register.

Figure 5 is a vertical sectional view taken at right angles to the sectional view shown in Figure 3.

Figure 6 is a detail top plan view of the actuating pawl.

Referring now to the drawings, the numeral 1 designates a register for controlling the passage of hot air from a suitable heater 2 to the interior of a vehicle body 3. As shown, the register is preferably located in the floor 4 of the vehicle body and is connected to the heater 2 by means of a suitable conduit 5. In detail, the register comprises a tubular body or casing 6 and apertured cover 7. As shown, the casing 6 is provided at one side thereof with an air inlet opening 8 surrounded by a tubular fitting 9 connected to the air supply conduit 5 and is provided at its upper end with a flared portion 10 that terminates in an an-

nular flange 11. The cover 7 has an annular portion 12 that surrounds and is preferably welded to the flange 11 of the casing 6. To provide a neat joint, the floor 4 of the vehicle body is provided with an opening 60 13 to receive the annular portion 12 of the cover, while the latter is preferably provided at the lower edges of the annular portion 12 with a lateral flange 14 that is secured to the lower face of the floor 4. 65

Located within the casing 6 is a disk valve 15 that is adapted to control the passage of air from the conduit 5 to the interior of the vehicle body. As shown, this valve 5 is rigidly secured to a pivot pin 16 70 journaled in the side walls of the casing 6 and is adapted to be moved on said pivot from the position shown by full lines to the position shown by dotted lines in Figure 5 of the drawings for directing the hot air 75 alternately through the apertured cover 7 and discharge opening 17 at the lower end of the casing 6. To facilitate the movement of the valve 15 to open or closed positions, I preferably provide a suitable coil spring 80 18 that is terminally secured to the crank portion 22 above the pivot 16 and to a lug 19 secured to the casing 6 at the lower end thereof. Thus, with this construction, the spring 18 will urge the valve 15 to open or closed positions after the valve is moved beyond dead center and will be effectively held by said spring in such open or closed positions. 85

For actuating the valve 15, I preferably provide a pawl 20 having an open ended slot 21 receiving the crank portion 22 of the pivot pin 16 and having a vertical opening 23 for receiving the shank 24 of a horizontally extending operating handle 25 disposed above the cover 7. As shown, a bracket 26 secured to the casing 6 supports the pawl 20 which in turn is held on the shank 24 of the operating handle by means of a cotter pin 27 located preferably beneath the bracket 26. It will also be noted that the opening 23 in the pawl 20 is provided with a flat side 28 that is engaged by the correspondingly flattened portion 29 of the shank 24, hence the handle 25 is non-rotatably connected to the pawl 20, however the opening 30 in the bracket 26 is circular so that the shank 24 may be free to turn therein. Thus, with this construction, the slotted free end of the pawl 20 will be swung to 110

right or left by the horizontal manipulation of the handle 25 above the register cover 7. As a result, the crank portion 22 of the pivot pin 16 will be rocked to open or 5 close the valve 15.

In use, the valve 15 may be moved by the handle 25 to open position shown by full lines in Figure 5 or may be moved to closed position shown by dotted lines. When in

10 open position the hot air from the conduit 5 will be directed by the valve 15 through the apertured cover 7, while in closed position the hot air will be directed downwardly through the open lower end of the casing 6.

15 Inasmuch as this opening 17 at the lower end of the casing is in alignment with the open upper end thereof, it will also be apparent that dust, dirt, in fact sediment of ^{any} kind collecting or finding its way in the casing 6

20 will readily fall through the lower opening 17 when the valve 15 is moved from open to closed position. Hence, this form of register may be easily and quickly cleaned. Moreover the operation of the movable parts is 25 exceptionally simple and dependable. It will also be apparent that the parts of the register may be readily assembled and the latter easily installed wherever desired.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim as my invention is:

1. The combination with the flooring of a vehicle body having an opening therein, of 40 an air register comprising an upright open ended body located in said opening and having a lateral inlet opening for air below the flooring, and a valve in the body opposite to the inlet opening alternately adjustable from 45 a position inclined upwardly from the lower

edge of said opening to a position inclined downwardly from the upper edge of said opening, the arrangement being such that foreign matter and sediment falling into the upper end of said body would be discharged 50 through the lower end of said body when said valve is in a position intermediate the inclined positions aforesaid.

2. The combination with a vehicle body having an opening therein for air, of an air register comprising a body located in said opening, said body having substantially aligned outlet openings for air and an inlet opening for air intermediate said outlet openings, a perforated cover for said body, a 55 valve in the body opposite to the inlet opening alternately adjustable from a position inclined upwardly from the lower edge of said opening to a position inclined downwardly from the upper edge of said opening, the arrangement being such that foreign matter and sediment falling through the perforations in said cover into said body will be discharged from said body when said valve is in a position intermediate the inclined positions aforesaid.

3. The combination with the flooring of a vehicle body having an opening therein, of an air register for vehicle bodies comprising a body located in said opening and projecting a short distance below said flooring, said body having vertically aligned outlet openings for air and a lateral inlet opening for air intermediate said aligned outlet openings, and a disc valve pivotally mounted in 75 the body opposite to said inlet opening, said valve being constructed and arranged in such a way that it may be moved on its pivot from a position inclined upwardly from the lower edge of said opening to a position inclined 80 downwardly from the upper edge of said opening.

In testimony whereof I affix my signature.

JAMES J. SUNDAY
